UNITED STATES PATENT OFFICE.

FREDERICK MILHAHN, OF DWIGHT, ILLINOIS.

STIRRING DEVICE FOR CALDRONS.

1,401,806.

Specification of Letters Patent. Patented Dec. 27, 1921.

Application filed May 12, 1921. Serial No. 469,026.

To all whom it may concern:

Be it known that I, FREDERICK MILHAHN, a citizen of the United States, residing at Dwight, in the county of Livingston and

5 State of Illinois, have invented certain new and useful Improvements in Stirring Devices for Caldrons, of which the following is a specification, reference being had thereto in the accompanying drawings.

10 This invention relates to caldrons and has for an object to provide a means for stirring the contents of a caldron at a distance removed from the caldron itself, whereby the operator is protected from the heat and 15 discomfort of close proximity to the caldron.

A further object of the invention is to provide, in combination with a caldron, an agitator adapted to rotate within the caldron and scrape the sides thereof, with operating means extending from the caldron to a point of comfort, with means at such point for operating the agitator.

With these and other objects in view the invention comprises certain novel parts, units, elements, combination and functions as disclosed in the drawings together with mechanical equivalents thereof as will be hereinafter more fully described and claimed.

30 In the drawings:

Figure 1 is a view in side elevation of a conventional caldron with the agitator applied thereto;

Fig. 2 is a top plan view of such caldron and agitating means;

Fig. 3 is a transverse or diametrical sectional view through the caldron showing the agitating operating means in section;

Fig. 4 is a detail fragmentary sectional view showing the means of attaching the device to a caldron;

Fig. 5 is a view in elevation of the shaft journaling support, and

Fig. 6 is a detail perspective view of a fragment of the agitator.

Like characters of reference indicate corresponding parts throughout the several views.

The device of the present invention is 50 adapted for and intended to be used with caldrons of various styles, shapes and sizes, as indicated conventionally at 10. Conventional caldrons are ordinarily provided with ears 11 diametrically disposed and the pres-

55 ent device comprises a spider 13 having means, as the hooks 12, for engaging the

ears of such caldron, said hooks extending through slots 14 in the spider and provided with winged nuts 15 for attaching the device to the caldron.

60 The spider 13 serves as a bearing to journal the shaft 16 which extends upwardly above the spider and is provided with a gear 17 secured thereto.

Upon the spider is also mounted a bearing box 18 journaling a shaft 19 which carries a pinion 20 inter-geared with the gear 17.

65 The shaft 19, or an extension thereof, 21, is provided with a crank 22 by which the pinion 20, the gear 17 and shaft 16 are rotated. The shaft 19, or 21 extended, is journalled in the bearing 23 supported by an adjustable upright 24 having a base 25 bearing upon the ground or floor. The adjustment is accomplished by means of a slot 26 70 in one of the members of the upright 24, through which a bolt 27 extends having a winged nut 28 for exerting stress on said bolt for the purpose of clamping together 75 the sections of the upright. The adjustment is for the purpose of attaining alinement between the bearings 23 and 18, whereby the shaft 19, or 21 extended, will operate freely.

80 The shaft 17 carries a cross-head 29, to which is adjustably secured a bendable hoop 30, the adjustment and the flexibility of the hoop providing for the curvature of the hoop 30 to conform to the curvature of the interior of the caldron, so that as said hoop rotates under the action of the rotating shaft 16 it will scrape the interior of the caldron, 85 agitating the contents and clearing the sides from adherents. The adjustment of the hoop 30 relative to the cross-head 29 may be 90 accomplished in the ordinary manner by having the cross-head provided with perforations 31 and the hoop with perforations 32, through which are extended bolts 33.

95 The caldron is supported in any usual and ordinary manner, as by the tripod 34, so that a fire may be maintained beneath the caldron in the usual and ordinary manner of operation.

100 It is believed that the utility and operation of the device will be perfectly apparent from the foregoing description and inspection of drawings and that further description will be unnecessary.

105 What I claim to be new is:

110 1. A hoop-shaped scraper composed of yielding material adapted to conform and

hold itself in direct contact with a container having a curvaform bottom, and means to vary the circumferential extent of the scraper to adapt it to bottoms of different radii.

2. The combination with a rigid container having a curvaform bottom, of a scraper comprising a hoop of yielding material adapted to conform itself to and move in direct contact with the bottom, and means to rotate the scraper.

3. The combination with a rigid container

having a curvaform bottom, of a scraper comprising a hoop of yielding material adapted to conform itself to and move in direct contact with the bottom, means to vary the circumferential extent of the hoop, and means to rotate the scraper.

In testimony whereof I hereunto affix my signature in presence of two witnesses.

FREDERICK MILHAHN.

Witnesses:

C. J. AHERN,
ANGELENE STEICHEN.
